TURBINE BUCKET

Kenneth M. Bartlett, South Euclid, Ohio, assignor to
Thompson Products, Inc., Cleveland, Ohio, a corpora-
tion of Ohio

Application July 8, 1948, Serial No. 37,670

8 Claims. (Cl. 253—39.15)

This invention relates to an air cooled axial flow 15 turbine.

In jet engines or the like there is usually provided an axial flow turbine operated by the exhaust gases which drives a blower furnishing air pressure to the burners. Such turbines operate at very high temperatures and it is, therefore, desirable to provide suitable means of cooling the buckets in order to reduce the temperature at which the turbine operates.

It is an object of the present invention to provide an axial flow turbine which will operate at lower temperatures than similar turbines now in use.

A further object of the invention is to provide an axial flow turbine bucket having adequate radial passages for the circulation of suitable cooling fluid.

A further object of the invention is to provide an axial flow turbine bucket which will be self-cooling.

A still further object of the invention is to reduce the cost and to increase the life of turbine buckets.

A still further object of the invention is to increase the efficiency of high temperature axial flow turbines.

Other objects will become apparent when considering the following specification which, when taken in conjunction with the accompanying drawings, illustrates a preferred embodiment of the method and apparatus.

In the drawings:

Figure 1 is a vertical cross section through an axial flow turbine and bucket thereof, which embody the present invention, the figure showing the air passages through the bucket;

Figures 2 and 3 are cross sections of the bucket taken on the lines II—II and III—III, respectively, of Figure 1;

Figure 4 is a longitudinal cross section through the core of the turbine bucket shown in Figure 1 prior to casting and illustrating in chain lines the outline of the bucket body cast around the core;

Figures 5, 6, 7, and 8 show successive steps in the formation of the core;

Figure 9 shows a core mounted in position in a mold for forming a wax pattern to be invested in a casting mold;

Figure 10 is a perspective view of the completed bucket;

Figure 11 is a plan view of the bottom section of an engraved graphite mold containing a relatively low melting point casting to provide a pattern for the core portion of a bucket according to a modified feature of this invention;

Figure 12 is a cross sectional view taken along the line XII—XII of Fig. 11 and including the top portion of the mold;

Figure 13 is a transverse cross sectional view of the cast body of Fig. 11 after depositing a thin coating of relatively high melting point metal or alloy thereupon to form a hollow core for the bucket according to the modified procedure of this invention;

Figure 14 is a view similar to Fig. 13 but showing the hollow core with the low-melting metal removed;

Figure 15 is an enlarged longitudinal cross section through the hollow core of Fig. 13 and illustrating in dotted lines the outline of the bucket body cast around the core to show how certain core portions protrude.

Referring to the drawings and particularly to Figure 1, the turbine is shown mounted on a shaft 15 and has a plurality of buckets 17 mounted between an inner plate 19 and an outer plate 20. The inner plate 19 may be carried on the shaft 15 by means of bolts 21

passing through a flange 22 formed on the end of the shaft. The shaft 15 may have a central aperture therethrough which communicates with the space 25 formed between the plates.

5 The buckets 17 are held between the plates by machine bolts 27 which clamp the plates and may grip the turbine buckets 17 between teeth 30 formed on the roots of the buckets 17 and on the peripheral marginal faces of the plates 19 and 20;

10 Each bucket 17 has a central opening 33 in its root or base which communicates with a plurality of passages 35 in its air foil section. The passages 35 extend radially through the air foil sections of the buckets so that as the plates 19 and 20 rotate with the buckets 17, air is forced by a compressor (not shown) through the passages 24 and 25, through the opening 33 in the base or root of the buckets and outwardly through the passages 35 in the air foil sections, thus insuring a continual stream of air moving through the central portion of the buckets to maintain the buckets at relatively cool temperatures.

The turbine shown is designed for high speed operation at very high temperatures and the buckets are quite small. For example, the actual size of the air foil portion of the bucket 17 may only be about one inch long by one-half inch wide (chord) by one-sixteenth inch maximum thickness. The passages 35 through the bucket 17 are correspondingly small, being approximately five-thousandths inch (.005") deep and twenty-thousandths inch (.020") wide. The passages are preferably spaced apart about ten-thousandths inch (.010"). It can therefore be appreciated that producing such small passages in such a small article is indeed difficult. The present invention utilizes a thin core to define the passages and this core is produced by electroplating a thin self-sustaining foil containing the passages.

The successive steps according to the present invention to form a cored turbine bucket having apertures therein of the size mentioned are shown in Figs. 4 to 9, inclusive. Referring to those figures, the first step in the method is to provide a master die 50 (Fig. 5), which has longitudinal ribs 51 therein corresponding in position to the passages 35 through the turbine bucket.

From the master die a matrix 54 is formed of a metal 45 having low melting point, the matrix having recesses 55 corresponding in position to the ribs 51 on the master die 50. The width and spacing of the recesses 55 is such that when the core material is formed over the matrix 54 the spacing and size of the passages 35 will correspond with that desired. The master die 50 is then separated from the matrix and a portion 56 (Fig. 6) of the core electroplated on the matrix 54. The partially completed core 56 has longitudinal grooves 57 corresponding in size and position to the passages 35 through the buckets.

55 The grooves 57 may then be filled with a filler material 58, such as aluminum, graphite, or a low melting point alloy, etc. (Fig. 7), and a second electroplating deposited on the partially completed core 56 to bridge the openings across the grooves 57 (as shown at 59) to complete the core, as seen in Figure 8.

As shown in Figures 4 and 9, the core 56 is wider at some portions 56a than the bucket. These portions 56a form core prints or supports to hold the core in position in a mold which forms either a wax casting cavity or a metal casting cavity.

60 It has been found desirable to have the material of the core of a high melting point alloy, which will have a slow rate of diffusion into the body metal of the bucket 17. One alloy which has been found to be suitable comprises 70% cobalt and 30% tungsten. If desired, a thin electroplating of a suitable alloy may be formed on the exterior of the core to further slow the diffusion rate of the core in the bucket casting.

75 After the core is completely formed, the backing material of the matrix is melted away to free the complete core with the filler material in the passages thereof. The core 56 is then mounted on a permanent mold section 62 with the support portions 56a of the core holding the core in proper position in the mold cavity. The top section 63 of the mold clamps the core in fixed relation in

the cavity and the core is then invested in a wax pattern 64. The wax pattern 64, with the core embedded therein, is invested in a ceramic mold (not shown) and the wax melted out. The bucket body is then cast around and welded to the core in the usual manner and the supports 56a are ground off flush with the edges of the body.

If graphite has been used as a filler material in the core, it can be diffused into the bucket. If aluminum has been used as a filler, it may be dissolved in sodium hydroxide, and if a low melting point alloy has been used, it may be melted out of the passages.

The material of the bucket should be one having a high resistance to corrosion at high temperatures and having a high tensile strength. Suitable materials are chrome steels and cobalt base chromium, molybdenum or tungsten alloys.

After casting, if a diffusible core metal has been used, the bucket may be heat treated to diffuse the material of the core into the bucket material, thus giving a bucket of substantial uniform consistency and of high rigidity and strength.

In some instances, it may be desirable to prevent the diffusion of the core into the body metal of the bucket and if the core metal is relatively diffusible it may be coated with a relatively non-diffusible material such as another metal, a ceramic material, or the like.

Another embodiment of the present invention is shown in Figures 11 through 15 wherein a hollow core is plated around a low-melting core pattern.

Figure 11 shows a core pattern or casting 65 of low-melting point metal, or alloy, such as Wood's metal, white metal, lead solder, or the like, resting in the bottom half of a mold 66. The mold 66 is preferably made of carbon, and is suitably engraved to provide a mold for forming the casting. The casting of low-melting metal has a sprue portion 67, and a relatively heavy substantially rectangular frame or support 68 extends from the sprue to form side legs and an end leg. A plurality of thin rounded veins or fingers 70 extend from a solid web portion 69 and in spaced relation from each other to one side leg and to the end leg of the frame 68. The web portion 69 is joined with the sprue end of the frame 68. The interior dimensions of the frame 68 are somewhat wider and longer than the dimensions of the bucket which is ultimately cast around it, as shown in Figure 15.

The casting 65 of the low melting point metal thus produced is next coated with a very thin layer of coating metal which forms the core of the finished bucket. The thickness of the metal layer is normally on the order of about 0.002 inch, and may be incorporated onto the surface of the casting by electroplating, hot dipping, or any suitable method which will deposit a thin layer of metal on the casting. The coating metal to be utilized is one which will not readily dissolve or disperse into the body of the metal used to form the core pattern, and will have a relatively slow rate of diffusion into the bucket metal. Suitable coating metals include nickel, cobalt-tungsten alloys, or the like. If desired, the casting may first be plated with a coating of nickel, followed by electroplating with chromium, to provide a nickel-chromium alloy composition plating. The sprue portion 67 may be severed from the assembly before or after the electroplating operation, as desired.

The low melting casting coated with a core metal of the type indicated is then heated to melt out the low melting body metal, and thus produce a self-sustaining hollow core 71 shown in Figures 14 and 15. The removal of the low-melting metal provides a structure having a wide and thin hollow inlet portion 69a feeding a plurality of hollow finger members 70a extending to one leg and an end of the hollow surrounding frame 66a. This frame portion 66a protects and holds the outer ends of the fingers 70a.

The core is then invested in wax to form the wax pattern for the bucket and may be supported in the wax investment mold by clamping the frame 66a between the mold sections in the same manner shown in Figure 9. The wax pattern containing the hollow core structure is then invested in a ceramic mold and the wax melted out. The bucket body is then cast around the core structure. As previously stated, the hollow fingers 70a extend to points beyond the edges of the bucket, so that when the bucket is trimmed, as shown by the chain lines 72 of Figure 15, the finger members 70a lie within

the vane or air foil section of the bucket and will provide passages from the hollow root, formed by the inlet 69a to two edges of the air foil.

From the foregoing description, it will be apparent that there has been provided a method of producing turbine buckets having openings therethrough for the passage of air, which method enables the bucket to be produced cheaply and which will give a more rigid bucket than may be obtained by other methods.

It is obvious that the disclosed method is subject to various changes and modifications, and that various changes in size, shape and arrangement of parts or steps may be made without departing from the spirit of the invention or the scope of the subjoined claims.

That which is claimed as new and is desired to be secured by United States Letters Patent, is:

1. A turbine bucket which comprises a body having an anchoring root at one end thereof and a curved foil portion extending from said root, a hollow core bonded in said body having a hollow tubular end in said root portion and hollow fingers extending from said end through said foil portion, some of said fingers being curved to terminate in the trailing side edge of the foil portion, other of said fingers terminating in the end of the foil portion remote from the root, said fingers providing passages joining the root with the end and the trailing side edge of the foil portion.

2. A core for a turbine bucket which comprises a hollow metal member having a hollow substantially rectangular frame, a hollow web portion on one leg of said frame extending therefrom into the space surrounded by the frame, a plurality of hollow fingers extending from said web and terminating in two legs of the frame including an end of the frame remote from the web carrying end, said core adapted to receive body metal around the web and plurality of hollow fingers with the frame holding said fingers in proper alignment in a mold or the like.

3. A metal core for a cast hollow turbine bucket or the like which comprises a generally rectangular frame, a thin flat hollow web extending from an end leg of said frame, a plurality of spaced hollow fingers extending from said web to the opposite end and a side edge of the frame, and said core adapted to be surrounded by body metal with the frame portion projecting beyond the body metal to hold the fingers and web in position in the body metal.

4. A turbine bucket comprising a bucket body portion bonded around a hollow core, said bucket body portion having fluid openings in the end and a side edge thereof, said core having a hollow root portion and a multi-passaged air foil portion, the passages in said air foil portion providing fluid directing means between said hollow root and said openings on said end and side edge of said bucket body.

5. A turbine bucket comprising a bucket body portion bonded around a hollow core composed of a thin metal network, said bucket body portion having fluid openings in the end and a side edge thereof, said network having passaged root and air foil sections defining vents through the bucket body to said openings on said end and side edge of said bucket body.

6. A fluid directing member comprising a metal body having a fluid directing foil portion having fluid openings on the end and a side edge thereof and an integral root portion for attachment to a wheel or the like, said metal body being bonded around a hollow core, said hollow core having a hollow root portion and hollow fingers communicating therewith, said hollow fingers defining passages from said hollow root portion to said openings on said end and side edge of the foil portion of the metal body.

7. A turbine bucket comprising a metal body having a fluid directing foil portion and an integral root portion bonded around a thin hollow core of metal, said foil portion having fluid openings on the end and a side edge thereof, said hollow core having a hollow root portion with a plurality of hollow passages in communication with said hollow root portion defining vents from the hollow root portion to said openings on said end and side edge of the foil portion of the metal turbine bucket body.

8. A fluid directing member comprising a metal body having a fluid directing foil portion and an integral anchoring root portion, said metal body being bonded

around a hollow metal core, said hollow core including a hollow tubular portion surrounded by said anchoring root portion, laterally spaced hollow legs on the sides of said hollow tubular portion and in communication therewith extending to a transverse hollow end leg and rec-coating therewith to form a hollow substantially rectangular frame surrounding said foil portion, said rectangular frame having laterally spaced hollow fingers attached to said transverse end leg and to one of said side legs and extending inside said frame to said hollow tubular portion and in communication with the hollow interior thereof, some of said fingers being curved and some of said fingers terminating in a longitudinal row and some of said fingers terminating in a transverse row respectively at said one side leg and said end leg of 15 said frame to provide a plurality of hollow passages for fluid flow from the hollow tubular portion of the core through the foil portion of the fluid directing member.
